REFRIGERATING MACHINE

Delbert F. Newman, Schenectady, N. Y., assignor
to General Electric Company, a corporation of
New York

Application February 17, 1937, Serial No. 126,211

5 Claims. (Cl. 62—116)

My invention relates to compression type refrigerating machines.

After a refrigerating machine of this type is placed in operation, subsequent to standing idle 5 for an interval of time sufficiently long for all of the elements thereof to assume an ambient temperature, a considerable period of time elapses before the machine is capable of lowering the temperature of the evaporator sufficiently to produce any quantity of useful refrigeration. This period of time is known as the "pull-down" period. Due to the relatively high temperature of the evaporator during the 10 initial portion of the "pull-down" period, the gaseous refrigerant drawn into the compressor and discharged into the condenser has a density considerably higher than normal, resulting in the compressor handling a much larger quantity of gaseous refrigerant than under normal operating 15 conditions. The condenser is designed to condense only the gaseous refrigerant at the normal rate of discharge from the compressor, in order to provide an economical construction. The machine is, therefore, incapable of condensing 20 the gaseous refrigerant at this increased rate of discharge from the compressor during the initial portion of this period, causing an abnormally high pressure to exist in the condenser. The compressor discharging against this abnor- 25 mally high pressure head in the condenser may cause the motor driving the compressor to become overloaded or stalled.

It is an object of my invention to provide a compression type refrigerating machine having 30 an arrangement for minimizing the increase in pressure above normal of the compressed refrigerant in the machine during the "pull-down" period of an evaporator associated with the machine from substantially an ambient tempera- 35 ture to an operating cooling temperature in order to prevent overloading of the compressor driving motor. I accomplish this by utilizing a refrigerant cooler interposed in the high pressure refrigerant circuit of the machine between 40 the compressor and the condenser, the refrigerant cooler being arranged in good heat exchange relationship with a heat absorbing body. Preferably, the refrigerant cooler is arranged in good heat exchange relationship with an hermetically 45 sealed casing enclosing the compressor and its electric driving motor in order to provide a compact machine.

Further objects and advantages of my invention will become apparent as the following description proceeds, and the features of novelty

which characterize my invention will be pointed out with particularity in the claims annexed to and forming a part of this specification.

For a better understanding of my invention, reference may be had to the accompany drawing, in which Fig. 1 is a side elevation of a refrigerator cabinet provided with a refrigerating machine embodying my invention, portions of the cabinet and machine being broken away to show more clearly the arrangement; and Fig. 2 is an enlarged fragmentary sectional view of the enclosing casing for the compressor and its driving motor and the refrigerant cooler arranged in good heat exchange relationship therewith.

Referring to the drawing, in Fig. 1 I have 15 shown a refrigerator cabinet 10 designed for domestic use which is provided with a heat insulated food storage compartment 11 in the upper portion thereof and a machinery compartment 12 arranged below the compartment 11. An 20 opening is formed in the front wall of the compartment 11 to afford access to the interior of the compartment and a heat insulated door 13 is hinged adjacent the marginal edge of this opening. Openings are formed in both the front 25 and rear walls of the machinery compartment 12 to afford ready access to the refrigerating machine arranged therein for purposes of inspection. A removable door 14 is arranged to cover the opening in the front wall of the machinery compartment 12 in order to give the 30 refrigerator cabinet a finished appearance.

The refrigerating machine includes a cylindrical hermetically sealed casing 15 in which an electric driving motor 16 and a refrigerant compressor 17 are arranged, the compressor being secured to the top of the motor. Preferably, the casing 15 is constructed of sheet steel and has a relatively large mass. The motor and the compressor are resiliently mounted in the casing 15 on a series of equally spaced helical compression springs 18. The upper ends of the springs 18 are secured to the frame of the motor 16 by a number of supporting feet 19 and the lower ends of the springs 18 are secured to the bottom wall or end of the casing 15. The springs 18 permit the motor and the compressor to move as a unit within the casing 15 and with respect thereto, thus preventing the transmission of vibration from the motor and the compressor to the enclosing casing. The casing 15 also contains a body of lubricant in the lower portion thereof which is recirculated to the moving parts of the motor and the compressor during the operation of the machine.

The casing 15 is substantially vertically disposed and is secured to a supporting frame 20 adjacent the rear of the machinery compartment 12. An air distributing hood 29 is secured to the supporting frame 20 adjacent the front of the machinery compartment 12 and is provided with an air inlet opening arranged in the front and bottom walls thereof for admitting cooling air into the machinery compartment below and adjacent the door 14. The upper portion of the hood 29 is securely braced by a strap 30 fastened to the casing 15. An air outlet opening 31 is formed in the wall of the hood 29 adjacent the casing 15 and a fan 32 is arranged in the opening 31 in order to draw the cooling air through the hood. The fan 32 is operated by an electric motor 33 supported upon the casing 15 by a bracket 34. Within the hood 29 and adjacent the outlet opening 31 there is arranged an annular frusto-conical air deflecting baffle 35 supported upon a series of studs 36. The cooling air drawn into the hood 29 by the fan 32 is distributed uniformly through the hood by the air deflecting baffle 35 and is discharged through the outlet opening 31. The baffle 35 also contributes toward quiet operation of the fan 32 by distributing the cooling air drawn through the hood 29 more uniformly adjacent the outlet opening 31.

During operation of the refrigerating machine 30 illustrated, gaseous refrigerant is drawn into the compressor 17 from the casing 15 through an intake muffler 37 and is compressed and discharged into an exhaust muffler 38, the intake and exhaust mufflers being arranged within the 35 enclosing casing 15. The compressed gaseous refrigerant is conducted from the exhaust muffler 38 by a flexible conduit 39 into a conduit 40 arranged exteriorly of the casing 15 and sealed in an opening in the bottom of the casing 15. The 40 conduit 40 communicates with a refrigerant cooler 41 disposed in good heat exchange relationship with the lower portion of the casing 15. This casing is formed of sheet steel and has a relatively large mass constituting a heat absorbing 45 body. Preferably, the refrigerant cooler 41 comprises a coil of copper pipe having a substantially half-round cross section, the flattened wall 41a of the coil being soldered to the periphery of the casing 15 as shown at 41b in Fig. 2. The compressed refrigerant, after passing through the 50 cooler 41, is conducted by a conduit 42 into the upper portion of a refrigerant condenser 43, the condenser 43 being arranged within the air distributing hood 29 adjacent the inlet opening in 55 the front and bottom walls of the hood. The condenser 43 is arranged in an inclined position to facilitate the flow of the refrigerant liquefied therein in a downward direction and is secured in place upon a wall of the hood 29 by bolts 44. The 60 compressed refrigerant is liquefied in the condenser 43 and flows from the lower portion thereof through a liquid conduit 45 into a suitable flow controlling float valve 46 arranged in the top of the cabinet, which regulates the quantity of liquid refrigerant supplied through a conduit 47 to a flooded type sheet metal evaporator 48. The evaporator 48 is positioned in the upper portion of the food storage compartment 11 and is suspended beneath the top wall thereof. The 70 liquid refrigerant contained in the evaporator 48 is vaporized by the absorption of heat from articles contained in the compartment in which the evaporator is located and the vaporized refrigerant is collected in a cylindrical header 49 75 which is normally maintained about one-half full

of liquid refrigerant. The vaporized gaseous refrigerant accumulating in the upper portion of the header 49 above the level of the liquid refrigerant therein is conducted through a conduit 50 into a coil 51 arranged in good heat exchange relationship with a tubular extension on the flow controlling float valve 46 in order to cool the liquid refrigerant supplied to the evaporator 48. The gaseous refrigerant is then returned to the interior of the casing 15 through a suction conduit 52. It will be noted that the discharge end 52a of the suction conduit 52 is located above the level of the body of lubricant contained in the lower portion of the casing 15. The gaseous refrigerant thus discharged into the casing 15 is again drawn into the compressor 17 through the intake muffler 37 and the cycle above described is repeated until the food storage compartment 11 in which the evaporator 48 is located is cooled to the desired temperature. Preferably, the liquid conduit 45 and the suction conduit 52 are arranged in a flexible enclosing conduit 53 extending from the machinery compartment 12 up the rear wall of the refrigerator cabinet to the upper portion of the cabinet 10.

The supporting arrangement for the enclosing casing 15 and the air distributing hood 29 permits the refrigerating machine to be readily placed into and removed from the machinery compartment 12 in assembled relation without disturbing the evaporator 48 in the food storage compartment 11.

During operation of the refrigerating machine, cooling air is drawn into the air distributing hood 29 by the fan 32 through the inlet opening in the front and bottom walls thereof below and adjacent the door 14 closing the opening in the front wall of the machinery compartment. The cooling air then flows uniformly through the refrigerant condenser 43 due to the arrangement of the air deflecting baffle 35 and is discharged through the outlet opening 31 about the casing 15 and the refrigerant cooler 41. The cooling air flows about the casing and refrigerant cooler and out of the machinery compartment through the opening in the rear wall of the compartment. Preferably, the fan driving motor 33 is arranged in a circuit with the compressor driving motor 16 and a suitable thermal control device which is operable to maintain any given average temperature over a predetermined range of temperatures within the food storage compartment 11, so that these motors are started and stopped simultaneously.

During the initial portion of the "pull-down" period the gaseous refrigerant drawn into the compressor 17 from the enclosing casing 15 has a density considerably higher than normal due to the relatively high temperature of the evaporator 48. Consequently, the compressor handles a much larger quantity of gaseous refrigerant during the initial portion of the "pull-down" period than under normal operating conditions. The condenser 43 is designed to condense only the gaseous refrigerant at the normal rate of discharge from the compressor in order to provide an economical construction. Thus, the machine is incapable of condensing the gaseous refrigerant at this increased rate of discharge from the compressor during the initial portion of this period. It is apparent that if the compressor 17 were arranged to discharge directly into the condenser 43, an abnormally high pressure would be built up in the condenser 43 during the initial portion of the "pull-down" period and that

the compressor discharging against this pressure head would overload the compressor driving motor 16. In fact, the driving motor 16 might become so heavily overloaded that it would become 5 stalled.

In order to minimize abnormally high pressures in the refrigerating machine during the initial portion of the "pull-down" period, the refrigerant cooler 41 is arranged in good heat exchange relationship with the casing 15 and is interposed in the high pressure circuit of the refrigerating machine between the compressor 17 and the condenser 43. All of the elements of the refrigerating machine including the casing 15 have a temperature 10 corresponding to ambient at the beginning of the "pull-down" period as previously pointed out, which temperature is considerably lower than the temperature of the compressed gaseous refrigerant discharged from the compressor. The casing 15 being constructed of sheet steel and having a relatively large mass, thus has a considerable capacity for absorbing heat from the refrigerant cooler 41 and the compressed gaseous refrigerant passing through the cooler during the initial portion of the "pull-down" period. The cooling action of the refrigerant cooler 41 upon the compressed gaseous refrigerant passing therethrough and entering the condenser 43 reduces the amount of superheat of the compressed gaseous 15 refrigerant and remains the same when it reaches the condenser 43, permitting the compressed gaseous refrigerant to be readily liquefied in the condenser at a relatively low pressure and to be supplied to the evaporator 48. It will be noted that the resilient mounting of the compressor driving motor 16 including the helical compression springs 18 spaces the motor within the enclosing casing 15 away from the side walls thereof, which spacing retards the flow of heat 20 from the motor to the casing. This mounting arrangement allows the refrigerant cooler 41 to utilize substantially all of the heat absorbing capacity of the casing 15 to cool the compressed gaseous refrigerant during the initial portion of 25 the pull-down period. Consequently, the existence of abnormally high pressures in the refrigerating machine are minimized.

The temperature of the casing 15 gradually rises upon operation of the machine during the 30 "pull-down" period due to the absorption of heat from the refrigerant cooler 41. The temperature of the casing approaches the temperature of the refrigerant cooler, at which point no pre-cooling of the compressed gaseous refrigerant is effected. In a similar manner, the density of the 35 gaseous refrigerant drawn into the compressor 17 from the casing 15 gradually decreases during the operation of the machine due to the lowering of the temperature of the evaporator 48, causing a corresponding gradual decrease in the rate of 40 discharge of the gaseous refrigerant from the compressor 17. Thus, the rate of discharge of the gaseous refrigerant from the compressor approaches normal, at which point no pre-cooling 45 of the compressed gaseous refrigerant is required by the condenser. From the above description of operation of the refrigerating machine, it will be understood that pre-cooling of the compressed gaseous refrigerant is required only during the 50 initial portion of the "pull-down" period to avoid abnormally high pressures in the refrigerating machine, and that the refrigerant cooler is operable to effect pre-cooling of the compressed gaseous refrigerant during this portion of the 55 "pull-down" period. On the other hand, it will

be understood that no pre-cooling of the compressed gaseous refrigerant is required during the normal operation of the refrigerating machine as the condenser is capable of condensing the compressed gaseous refrigerant at the normal rate of discharge from the compressor, and that the refrigerant cooler effects no appreciable pre-cooling of the gaseous refrigerant during normal operation of the refrigerating machine. 10

It will thus be seen that I have provided a compression type refrigerating machine having a compact arrangement for minimizing the increase in pressure above normal of the compressed refrigerant in the machine during the 15 "pull-down" period of an evaporator associated with the machine from substantially an ambient temperature to an operating cooling temperature.

While I have shown a particular embodiment 20 of my invention in connection with a refrigerating machine designed for domestic use, I do not desire my invention to be limited to the particular construction shown and described, and I intend in the appended claims to cover all modifications within the spirit and scope of my invention. 25

What I claim as new and desire to secure by Letters Patent of the United States is:

1. A refrigerating machine including a refrigerant compressor, means for driving said compressor, means including a condenser communicating with said compressor for liquefying the compressed refrigerant delivered thereto, an evaporator supplied with liquid refrigerant from 30 said condenser, a heat absorbing body, and means including a refrigerant cooler connected between said compressor and said condenser and arranged in good heat exchange relationship with said heat absorbing body for minimizing the increase in pressure above normal of the compressed refrigerant in the refrigerating machine during the "pull-down" period of said evaporator from substantially an ambient temperature to an operating cooling temperature, said last-mentioned means utilizing the heat absorbing capacity of 35 said body during the initial portion of the "pull-down" period for reducing the amount of superheat of the compressed refrigerant delivered to said condenser. 40

2. A refrigerating machine including a refrigerant compressor, a motor for driving said compressor, a casing enclosing said compressor and said motor, means including a condenser communicating with said compressor for liquefying the compressed refrigerant delivered thereto, an evaporator supplied with liquid refrigerant from 50 said condenser, and means including a refrigerant cooler connected between said compressor and said condenser and arranged in good heat exchange relationship with said casing for minimizing the increase in pressure above normal of the compressed refrigerant in the refrigerating machine during the "pull-down" period of said evaporator from substantially an ambient 55 temperature to an operating cooling temperature, said last-mentioned means utilizing the heat absorbing capacity of said casing during the initial portion of the "pull-down" period for reducing the amount of superheat of the compressed refrigerant delivered to said condenser. 60

3. A refrigerating machine including a refrigerant compressor, a motor for driving said compressor, a casing enclosing said compressor and said motor, means including a condenser 65

communicating with said compressor for liquefying the compressed refrigerant delivered thereto, an evaporator supplied with liquid refrigerant from said condenser, and means including a refrigerant cooler connected between said compressor and said condenser and arranged about said casing in good heat exchange relationship therewith for preventing overloading of said driving motor during the "pull-down period" of 5
10 said evaporator from substantially an ambient temperature to an operative cooling temperature, said last-mentioned means utilizing the heat absorbing capacity of said casing during the initial portion of the "pull-down" period for reducing 15
15 the amount of superheat of the compressed refrigerant delivered to said condenser.

4. A refrigerating machine including a refrigerant compressor, a motor for driving said compressor, a casing enclosing said compressor and 20 said motor, means including a condenser communicating with said compressor for liquefying the compressed refrigerant delivered thereto, an evaporator supplied with liquid refrigerant from said condenser, and means including a refrigerant cooler coil connected between said compressor and said condenser and arranged about 25
25 said casing in good heat exchange relationship therewith for minimizing the increase in pressure above normal of the compressed refrigerant in the refrigerating machine during the "pull-down" period of said evaporator from substantially an ambient temperature to an operative cooling temperature, said last-mentioned means utilizing the heat absorbing capacity of said casing during the initial portion of the "pull-down" period for reducing 26
30 the amount of superheat of the compressed refrigerant delivered to said condenser, and means for directing a current of cooling air over said condenser and thence over said cooler and said casing.

cooling temperature, said last-mentioned means utilizing the heat absorbing capacity of said casing during the initial portion of the "pull-down" period for reducing the amount of superheat of the compressed refrigerant delivered to 5
10 said condenser.

5. A refrigerating machine including a refrigerant compressor, a motor for driving said compressor, a casing enclosing said compressor and said motor, means including a condenser communicating with said compressor for liquefying the compressed refrigerant delivered thereto, an evaporator supplied with liquid refrigerant from said condenser, means including a refrigerant cooler connected between said compressor and 15
15 said condenser and arranged in good heat exchange relationship with said casing for minimizing the increase in pressure above normal of the compressed refrigerant in the refrigerating machine during the "pull-down" period of said 20
20 evaporator from substantially an ambient temperature to an operative cooling temperature, said last-mentioned means utilizing the heat absorbing capacity of said casing during the initial portion of the "pull-down" period for reducing 25
25 the amount of superheat of the compressed refrigerant delivered to said condenser, and means for directing a current of cooling air over said condenser and thence over said cooler and said 30
30 casing.

DELBERT F. NEWMAN.
